UNITED STATES PATENT OFFICE

ADOLPH PAUL MARTIN GUHL, OF HAMBURG, GERMANY

PENCIL-SHARPENING MACHINE

Application filed November 11, 1929, Serial No. 406,300, and in Germany December 13, 1928.

My invention relates to machines for sharpening pencils such as lead, chalk, slate and other pencils and crayons of that type in which both cutter and pencil holder are mechanically rotated during the sharpening process.

The principal object of this invention is to provide an improved pencil sharpening machine of the type set forth having a gage mechanism of simple design which is adapted to automatically stop the travel of the pencil towards the rotary cutter after the pencil has been sharpened to the desired degree.

The invention further aims at thus designing the gage mechanism concerned that it can be adjusted and reset at a moment's notice so as to control the formation of either a longer and sharper or of a shorter and broader pencil point.

Other objects of the invention will incidentally appear hereinafter.

The nature and scope of the invention are briefly outlined in the appended claims and will be more fully understood by the following specification, taken together with the accompanying drawing, in which:

Fig. 1 is a side elevation showing the principal structural features of the improved pencil sharpening machine by way of an example,

Fig. 2 is a plan of the machine,

Fig. 3 is another plan showing the gaging mechanism in a larger scale,

Fig. 4 is a cross section on line 4—4 in Fig. 1,

Fig. 5 is a front elevation partly in section along line 5—5 in Fig. 1.

On the frame of the pencil sharpening machine a shaft 1 is rotatably mounted having attached at one end a hand driven crown gear wheel 2, 3, the latter meshing with a pinion 4 by which a disc shaped side milling cutter 5, fixed on an exchangeable spindle 6, is revolved.

On standards provided at the upper part of the machine frame a bar or rail 11 is stationarily fixed serving as a guide member to a carriage 7 which is slidably mounted on the shaft 1 and laterally engages the guide bar 11 by means of upright lugs 12, 12'.

A chuck 8, adapted to hold the pencil 17 at its rear end and to rotate the same, is rotatably mounted on the carriage 7, said chuck having a pinion 10 attached to it which gears with another pinion 9, the latter being 55 slidably mounted on and rotated by shaft 1 and a key 1a, as indicated in the Figs. 4 and 5.

By moving the carriage 7 along shaft 1 the pencil 17 is driven ahead towards the cutter 5 and sharpened by the latter. The carriage 7 is adapted to be pushed forward by the operator of the machine, who embraces with one or more fingers one of the studs 11a, 60 projecting from the top of guide bar 11, and keeps another finger or thumb gently pressed against the lug 25 at the rear end of carriage 7.

The front end of the pencil 17 while being rotated and sharpened is held by a guide block 14 having a conical bore hole and a slot through which the sharpened section of the pencil laterally projects into the range of the cutter 5.

According to this invention a gage mechanism is provided for automatically terminating the advancement of the pencil and incidentally the cutting operation, said mechanism comprising the following structural elements:

A lever 18 is hinged at the right end of the machine frame near the hand wheel 2 and cutter 5, said lever having a gage or stop member 15 pivotally attached to it, which is adapted to be thrown by a handle 15a into the path of the pencil (Fig. 5), the point of which will eventually come into contact with the opposed face of the stop 15 and in turn swing aside lever 18.

As seen in Fig. 3 lever 18 is cooperatively connected through a link 26 with a toothed rack 20 having guide slots 21 obliquely arranged therein and being slidably mounted at the lower side of rail 11 by means of studs 22 and a spiral spring 24.

It will be noted that by reason of the oblique disposition of the guide slots 21 tooth-rack 20 on being pulled to the right against the action of spring 24 by lever 18 and link 26 will move laterally, viz., towards

a tooth 23 projecting from and fixed on the carriage 7 (Fig. 3), thereby stopping the latter on its travel and arresting the pencil in appropriate position relatively to the cutter 5.

5 Thus by touching the stop 15 and locking the carriage 7 the pencil automatically prevents its own further advancement towards and across the rotating cutter 5 and will 10 incidentally terminate the cutting and sharpening action of the latter.

15 Various changes and modifications may be made in the design of structural elements of pencil sharpening machines and in the cooperation of their component parts as described above, without substantially departing from the scope of the appended claims and deviating from the spirit and the fundamental ideas of this invention.

20 E. g., another gage or stop 16 may be provided at the handle 15a or on the stop 15 proper in staggered (advanced) position to the latter, as best seen in Figs. 3 and 5, so as to present a second contact member which 25 may be alternatively thrown into the path of travel of the pencil by the handle 15a— instead of stop 15—in cases when a shorter and broader point on the pencil is required.

25 The handle 15a may be adapted to be 30 swung backward so as to throw out of operation both stops 15 and 16 and may be arrested automatically on reaching its respective operative and inoperative positions, e. g., by lugs 18a projecting from the upright 35 section of lever 18, as indicated in Figs. 3-5.

On withdrawing the sharpened pencil the toothed rack 20 will return into its inoperative position by the action of spring 24, thus 40 unlocking carriage 7.

45 What I claim is:—

1. In a pencil-sharpening machine of the type comprising a stationarily mounted rotary cutter and a slidably mounted pencil holder which are mechanically rotated during the sharpening process, a gaging mechanism cooperatively connected with the pencil holder, and means controlled thereby to automatically lock the latter on its travel towards the rotary cutter after the pencil has 50 been sharpened.

55 2. In a pencil-sharpening machine of the type comprising a stationarily mounted rotary cutter and a slidably mounted pencil holder which are mechanically rotated during the sharpening process, a gaging mechanism cooperatively connected with the pencil holder, and adapted to automatically lock the latter on its travel towards the rotary cutter after the pencil has been sharpened, 60 said gaging mechanism comprising a toothed rack slidably mounted and adapted to be moved laterally toward the pencil holder, a locking element provided on the pencil holder and adapted to be engaged by the 65 said toothed rack, and means for actuating

said toothed rack, adapted to be controlled by the pencil point.

3. In a pencil-sharpening machine of the type comprising a stationarily mounted rotary cutter and a slidably mounted pencil 70 holder which both are mechanically rotated during the sharpening process, a gaging mechanism cooperatively connected with the pencil holder and adapted to automatically lock the latter on its travel towards the 75 rotary cutter after the pencil has been sharpened, said gaging mechanism comprising a toothed rack slidably mounted and adapted to be moved laterally toward the pencil holder, a locking element provided on the pencil holder and adapted to be engaged by the said toothed rack and means for actuating said toothed rack, adapted to be controlled by the pencil point, said actuating means comprising a lever hinged at 80 the machine frame and being cooperatively connected with the said toothed rack through a link and a spring, and a stop member pivotally attached to said lever and adapted to be thrown into the path of travel of the 85 pencil point.

90 In testimony whereof I affix my signature.

A. P. MARTIN GUHL.
